UNITED STATES PATENT OFFICE.

BENJAMIN HOOVER, OF MERIDIAN, MISSISSIPPI, ASSIGNOR OF ONE-HALF TO SWEBERT B. RIEG, OF MERIDIAN, MISSISSIPPI.

SAFETY APPLIANCE FOR RAILROAD-CARS.

1,210,803.

Specification of Letters Patent.

Patented Jan. 2, 1917.

Application filed September 20, 1916. Serial No. 121,262.

To all whom it may concern:

Be it known that I, BENJAMIN HOOVER, a citizen of the United States, residing at Meridian, in the county of Lauderdale and 5 State of Mississippi, have invented a new and useful Safety Appliance for Railroad-Cars, of which the following is a specification.

The present invention appertains to safety 10 appliances for railroad cars, and relates more particularly to a device for opening the train pipe in case of an accident, such as the derailment of a truck or the dropping of a brake beam, whereby the air 15 will escape to the atmosphere to apply the brakes and stop the train without doing appreciable damage or causing a wreck.

It is the object of the invention to provide a valve construction for the train pipe 20 which is normally held closed, and which is opened in the event of an accident, as above indicated, to let the air bleed to the atmosphere for applying the brakes, the valve structure being such as to be particularly desirable and efficacious for its intended purposes.

Another object of the invention is the provision of novel means for releasing the valve so that it will open in case of the dropping 30 of either one of the brake beams of a truck.

A still further object of the invention is the provision of novel means for operating the valve in the event of the excessive or abnormal turning of the truck, as in case of a 35 derailment.

It is also the object of the invention to provide an appliance of the nature indicated which is extremely simple and inexpensive in construction, which can be readily installed upon railroad cars, and which is 40 practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 50 within the scope of what is claimed without departing from the spirit of the invention.

The invention is illustrated in the accompanying drawing, wherein:—

55 Figure 1 is a side elevation of the appli-

ance, showing parts of a truck in section. Fig. 2 is a plan view of the appliance. Fig. 3 is a cross section taken on the line 3—3 of Fig. 2 on a slightly enlarged scale. Fig. 4 is a sectional view taken on the line 4—4 of Fig. 1 on a slightly enlarged scale.

In the drawing, only a portion of a railroad car and one truck is illustrated, but the showing is sufficient to enable the present invention to be readily understood and 65 appreciated.

The numeral 1 designates the train pipe extending under the car body 2, and a valve casing 3 is interposed in said pipe 1 adjacent to each truck. The casing 3 has an 70 standing boss 3^a provided with a concaved recess 5 providing a valve seat, there being an outlet port or aperture 4 leading from the bore of the casing 3 to the center of the recess or valve seat 5. A hemi-spherical 75 valve head 6 is disposed above the boss 3^a with its convexed surface uppermost to shed rain and other foreign matter to the sides of the valve casing away from the valve seat, and the head 6 has a radial extension 80 7 pivoted, as at 8, to the top of the valve casing 3, whereby the head 6 is swingable upwardly away from the valve seat by the pressure of the air, the valve seating by gravity when there is no air pressure. A 85

substantially hemi-spherical gasket 9 of rubber or other compressible material has its flat side bearing against the flat side of the head 6, and the gasket 9 is secured to said head by means of a screw 10 or other retaining element extending through the gasket and threaded into the head 6, the head of the screw being counter sunk and embedded in the gasket 9 so as not to contact with the valve seat. The gasket 9 is adapted to 90 seat snugly in the recess or valve seat 5, to provide an effective closure for normally preventing the escape of air through the port 4. The free portion of the head 6 has a depending finger 11 provided with an outstanding lug 12 having an upper rounded 95 surface.

One end portion of the casing 3 is reduced, as at 13, and has mounted for rotation thereon, a ring or collar 14 held in 100 place by means of a nut or retaining element 15 engaged upon the reduced end portion 13. The upper portion of the ring 14 is provided at one side with a lug 16 of arcuate section projecting therefrom toward 110

the boss 3^a to move over the lug 12 by a cam action, for depressing said lug 12 and for holding it depressed so as to seat the gasket 9 in the recess 5, whereby the valve is held closed.

5 The ring 14 has a depending arm 17 provided with a bore 18 in which a detent ball 19 is movable, the bottom of the end portion 13 having a rounded recess 20 for receiving the ball 19 under the influence of a coiled wire expansion spring 21 housed in the bore 18 and pressing said ball 19 against the portion 13. The spring 21 is held in place by a removable plug 22 threaded into the bore 18, and the ball 19 in engaging in the recess 20 will hold the ring 14 in place against accidental displacement, but the ring 14 can be rotated in either direction by force, to release the valve and permit it to swing open, whereby to discharge the air from the train pipe to apply the brakes.

10 As a means for operating the valve in case of the derailment of the truck, a bar 23 has an offset end secured, as at 24, upon the bolster 25 of the adjacent truck, and the bar 23 projects longitudinally from the truck under the valve, and has its free end portion bent back, as at 26, to provide a loop through which the arm 17 depends, whereby should the truck be derailed, the bar or bracket 23 will be swung toward one side or the other, so that the arm 17 will be swung likewise. When the arm 17 is swung sufficiently in either direction, the lug 16 is removed from the lug 12, so that the valve can be thrown open by the air pressure.

15 As a means for releasing the valve in the event that one of the brake beams is accidentally dropped, a rock shaft 27 is journaled in a transverse position below the body 2 by bearings or hangers 28 carried by said body, and hangers 29 are carried by the shaft 27 and are provided at their lower ends with arms 30 extending longitudinally under the brake beams 31 of the truck. Should either or both of the brake beams be loosened, they will be caught by the arms 30 and supported, to prevent a wreck or other accident, and this will swing 20 the hangers 29 due to the depression of the arms 30 by the weight of the brake beam or beams. The arms 30 are normally raised by means of a coiled wire retractile spring 32 connecting one arm and the body 2, although any other suitable spring means can be used for this purpose. A chain 33 or other flexible element has one end connected to one arm 30, the chain 33 and spring 32 being preferably at that side of the brake beams opposite the hangers 29, whereby to prevent the brake beams from sliding off of the arms 30 when they are dropped. The chain 33 passes over pulleys or guides 34 hung from the body 2, and the chain passes 25 and bears against the bent back portion 26

and from there extends downwardly through an apertured ear or eye 35 projecting to one side from the lower end of the arm 17. A ball or other suitable weight 36 is attached to the free end of the chain 33 below the ear 35 and is of sufficient size that it cannot pass through said ear when the chain is pulled. The chain is pulled whenever the arms 30 are depressed, whereby the weight 36 in contacting with the ear 35 will result 30 in the arm 17 being swung to release the valve. The weight 36 in pulling the chain, will hold the same taut, to take out the slack, and this will prevent the rattling or loose play of the parts.

35 Having thus described the invention, what is claimed as new is:—

1. A safety appliance for railroad cars embodying a valve casing to be interposed in a train pipe and having a boss provided with a concaved recess, the casing having an outlet port centrally of said recess, a valve head pivotally connected with the valve casing, a hemi-spherical gasket having its flat side fitting said head and seatable snugly in said recess, securing means extending through the gasket and into the head, means carried by the casing for holding said head with the gasket seated in said recess, and means for releasing said holding means.

40 2. A safety appliance for railroad cars embodying a valve adapted to be interposed in a train pipe, an oscillatory member carried by the valve for holding it closed when said member is in one position, said member having a guiding element, a flexible element extending through said guide element, and a weight carried by said flexible element for holding it taut and adapted to contact with said guiding element when the flexible element is pulled for swinging said member to release the valve.

45 3. A safety appliance for railroad cars embodying a normally closed valve adapted to be interposed in the train pipe, a swinging device adapted to be hung from a car body and having means to extend below the brake beams of a truck for catching them, whereby said device is swung, and means whereby when said device is swung the valve 50 is operated to open it.

55 4. A safety appliance for railroad cars embodying a normally closed valve to be interposed in a train pipe, a rock shaft adapted to be carried by a car body, hangers carried by said shaft and having arms extending therefrom to be disposed below the brake beams of a truck for catching and supporting said beams whereby the arms are depressed and the hangers swung, and means 60 operable when said arms are depressed for operating the valve so that it opens.

65 5. A safety appliance for railroad cars embodying a normally closed valve, an oscillatory member assembled therewith for 65

holding the valve closed when in one position, said member having a guide element, a rock shaft adapted to be hung from a car body, hangers carried by said shaft and having arms projecting therefrom to be disposed below the brake beams of a truck, a guided flexible element attached to one of said arms and extending through said guide element, a weight attached to the flexible element to contact with the guide element

when the chain is pulled by the depression of said arms, and spring means for normally raising said arms.

In testimony that I claim the foregoing as my own, I have hereto affixed my signature 15 in the presence of two witnesses.

BENJAMIN HOOVER.
